UNITED STATES PATENT OFFICE.

HENRY KAISER, OF DETROIT, MICHIGAN.

SHOE.

1,253,496.

Specification of Letters Patent. Patented Jan. 15, 1918.

Application filed May 31, 1916. Serial No. 100,755.

To all whom it may concern:

Be it known that I, HENRY KAISER, a citizen of the United States of America, residing at Detroit, in the county of Wayne and State of Michigan, have invented certain new and useful Improvements in Shoes, of which the following is a specification, reference being had therein to the accompanying drawings.

10 In the use of bellows tongues for shoes, especially those used by woodsmen, miners, sportsmen or the like, it is desirable that that portion of the tongue which lies just above the vamp be a waterproof protection 15 through which the snow and moisture which are liable to collect will not penetrate.

This invention relates to a tongue for lumbermen's rubbers, shoe packs, shoes or the like and to an arrangement thereof, whereby 20 that portion which is most liable to encounter moisture is made water proof without impairing the flexibility of the tongue or causing discomfort to the wearer.

The invention consists in the matters hereinafter set forth, and more particularly 25 pointed out in the appended claims.

In the drawings,

Figure 1 is a view of a shoe tongue applied to a rubber, embodying features of the 30 invention;

Fig. 2 is a plan view in detail of the lower portion of the tongue;

Fig. 3 is a view partially in section and partially in perspective, of a portion of the 35 tongue, and

Fig. 4 is a view in transverse section of a modification thereof.

As shown herein, a rubber or shoe having a counter 1 and vamp 2 of standard type is 40 provided with a quarter 3 to which a bellows tongue 4 is secured by lines of stitching 5 on either margin in the customary way, the quarter and bellows tongue being stitched as at 6 to form a lap seam over the upper edge 45 of the vamp and counter. Between the lines of stitching 5 (see Fig. 2), a shield 7 is applied of suitable shape to smoothly overlie the contiguous portion of the bellows tongue

4 while there is considerable clearance between the marginal portion 8 of the shield 50 and the adjacent lines of stitching 5. This is afforded by the general contour of the shield 7 and by the incurved marginal portions 9 and 10 thereof.

The shield is preferably of waterproof 55 material, such as properly treated leather or the like, and it may be of a single piece as indicated in the detail view of Fig. 3, or it may consist of an outer layer of leather 11, and an intermediate layer of pantosote or 60 like waterproof fabric 12, as shown in Fig. 4.

As a result of the construction, a shoe is obtained that fits smoothly over the instep of the wearer and presents a tongue which is impervious to water at the point where 65 snow and water are most likely to collect, and that thereby prevents any discomfort to the user.

Obviously, changes in the details of construction may be made without departing 70 from the spirit of my invention, and I do not care to limit myself to any particular form or arrangement of parts.

What I claim is:—

1. The combination of the vamp of a shoe 75 with a tongue including a shield of waterproof material appropriately secured along its margin to the lower portion of the shoe tongue between the margins thereof and arranged with the tongue to overlie the contiguous margin of the vamp.

2. The combination with the quarters of a shoe of a bellows tongue stitched thereto along its edges having a shield of waterproof material conformed to the lower portion 85 thereof and secured to the outer face thereof by stitching along the margin of the shield that is within the line of stitching of the tongue to the quarters.

3. The combination with a shoe having a 90 bellows tongue stitched to the vamp and quarters thereof, of a shield of waterproof material secured along its margin to the outer face of the lower portion of the tongue, by lines of stitching completely within and 95 separate from the lines of attachment of the tongue to the quarters, the tongue and shield having lower registered margins adapted to overlie the contiguous margin of the shoe vamp.

In testimony whereof I affix my signature in the presence of two witnesses.

HENRY KAISER.
